UNITED STATES PATENT OFFICE.

CHRISTIAN F. NAST, OF CHICAGO, ILLINOIS, ASSIGNOR TO CHICAGO PORTRAIT COMPANY, OF CHICAGO, ILLINOIS, A CORPORATION OF ILLINOIS.

DESIGN FOR A PICTURE FRAME.

Application filed July 2, 1926. Serial No. 18,234. Term of patent 3½ years.

To all whom it may concern:

Be it known that I, CHRISTIAN F. NAST, a citizen of the United States, residing at Chicago, in the county of Cook and State of Illinois, have invented a new, original, and ornamental Design for Picture Frame, of which the following is a specification, reference being had to the accompanying drawing, forming part thereof.

In said drawing Fig. 1 is a front elevation of a picture frame, showing my new design applied to one-half of the frame, and Fig. 2 is a vertical cross section thereof taken on the line 2—2 of Fig. 1.

The decoration illustrated, is carried about the opposite end of the frame.

I claim:

The ornamental design for a picture frame as shown.

CHRISTIAN F. NAST.
